US00D764062S

(12) **United States Design Patent**
Dennewald(10) **Patent No.:** **US D764,062 S**
(45) **Date of Patent:** **** Aug. 16, 2016**(54) **ORTHOTIC DEVICE**(71) Applicant: **Adrian Dennewald**, Waverton (AU)(72) Inventor: **Adrian Dennewald**, Waverton (AU)(73) Assignee: **DENNEROLL HOLDINGS PTY LTD**,
Cromer, NSW (AU)(**) Term: **14 Years**(21) Appl. No.: **29/473,673**(22) Filed: **Nov. 25, 2013****Related U.S. Application Data**

(60) Continuation of application No. 13/750,084, filed on Jan. 25, 2013, now Pat. No. 8,713,732, which is a continuation of application No. 12/468,547, filed on May 19, 2009, which is a division of application No. 11/524,560, filed on Sep. 21, 2006, now abandoned.

Primary Examiner — T. Chase Nelson*Assistant Examiner* — Mark Cavanna(74) *Attorney, Agent, or Firm* — King & Schickli, PLLC(57) **CLAIM**

The ornamental design for an orthotic device, as shown and described.

DESCRIPTION

FIG. 1 is a perspective view of an orthotic device according to my new design; and,

FIG. 2 is a left elevation view of the device of FIG. 1. The broken lines are included for the purpose of illustrating portions of the orthotic device that form no part of the claimed design.

1 Claim, 1 Drawing Sheet(56)
